UNITED STATES PATENT OFFICE.

EDWARD J. BRANDT, OF WATERTOWN, WISCONSIN, ASSIGNOR TO BRANDT CASHIER COMPANY, OF CHICAGO, ILLINOIS, A CORPORATION OF ILLINOIS.

DESIGNATING, RECORDING, AND REGISTERING APPARATUS.

967,716.

Specification of Letters Patent. Patented Aug. 16, 1910.

Application filed March 30, 1907. Serial No. 365,438.

To all whom it may concern:

Be it known that I, EDWARD J. BRANDT, a citizen of the United States, and resident of Watertown, in the county of Jefferson and State of Wisconsin, have invented certain new and useful Improvements in Designating, Recording, and Registering Apparatus; and I do hereby declare that the following is a full, clear, and exact description thereof.

The invention has for its object to provide for recording sales in a mercantile establishment, as well as to provide for automatic registration of the sum total money value of successively recorded sales; said invention consisting of what is herein shown, described and claimed as pertaining to a peculiar indicator-sheet and a machine employed in conjunction with a succession of punched indicator-sheets, one at a time, to record predesignated sale amounts on sales-tickets, or to register sum total money value of a succession of cash transactions or both, each punched indicator-sheet being of itself a permanent sale record.

Figure 1 of the accompanying drawings represents a vertical longitudinal section view of a combined recording and registering machine in which to utilize punched indicator-sheets successively, each of said sheets properly positioned in the machine being the means governing a recording or registering operation or both of the machine, said view being indicated by line 1—1 in Fig. 4; Fig. 2, a plan view of the machine having casing portions thereof in horizontal section, as indicated by lines 2—2 in Fig. 1; Fig. 3, a plan view of the machine partly in horizontal section as indicated by lines 3—3 in Fig. 5; Figs. 4 and 5 transverse sectional views of the machine respectively indicated by lines 4—4 and 5—5 in Fig. 1, the figures thus far being on a reduced scale as compared to that of the machine itself; Fig. 6, a partly sectional view illustrating a full size slip-clutch detail in the register-mechanism of the machine; Fig. 7, a face view of a full-size combined spur and register-wheel in said mechanism, Fig. 8, a side elevation partly in section illustrating the relative arrangement of multiplying wheels in the aforesaid mechanism; Fig. 9, a plan view of a full size punched indicator-sheet, and Fig. 10, a sales-ticket after treatment of same in the machine, this ticket having

been originally an appendix of the indicator-sheet from which it is torn on a line of perforations.

Referring by letter to the drawings, A indicates one of the aforesaid indicator-sheets, the face of which is arbitrarily spaced; this spacing being preferably a display of characters of the Arabic notation in columns longitudinally of the sheet at regular recurring intervals, which characters in each column are likewise at regularly recurring intervals in ascending order beginning with the cipher, and reading from right to left transversely of said sheet, as it appears in Fig. 9, said columns of numerical characters being in the ascending order of said notation beginning with units.

As a matter of convenience, in practice, each indicator-sheet may be originally integral with the blank of a sales-ticket B such as is herein shown by Fig. 10, in condition for delivery to the buyer of goods indicated thereon, said sheet and ticket having been parted on a dividing line of perforations.

The aforesaid machine comprises a frame having a base C, side-standards D and an end-piece E suitably connected. Arranged on the base C are spacers F and a suitably perforated plate G is laid in on the spacers. Set on the plate G, longitudinally of the same at suitable intervals apart, are a series of rails H provided with lateral spacing lugs b, and engaging these rails and lugs are tie-rods c in connection with the frame-standards aforesaid, as best illustrated in Fig. 4.

The perforations in the aforesaid plate match those of a die-plate I set in the frame-base C flush with the top of same, said base being slotted under the die-plate. The perforations of the plates G, I, guide the depending pins of perforating punches J hereinafter more particularly described, and in their descent said pins cross a space provided between the frame-base C and plate G aforesaid, this space being open at one side of the machine for the introduction of a sales-ticket or other device in which to punch a record. The space opening is preferably flaring to facilitate the placing of the record device in the machine.

The side-standards D of the aforesaid frame, and the rails H parallel to same are provided with vertical recesses and counter-

sunk sockets, the recesses being lapped by the ends of plates *d* set flush in upper edges of said standards and rails. These plates serve as stops in opposition to head-shoulders *e* of pins *f* engaging spiral-springs *g* seated in the aforesaid sockets, and thus upward movement of the pins, under expansive force of the springs, is limited, each pin-head being normally flush with a pair of the plates *d* to bridge the gap between same, as clearly shown in Figs. 1 and 3.

Guided on the frame-standards *D* and the rails *H*, as best shown in Fig. 5 are heads of the punches *J*, these punches being longitudinally slotted, and strung, in series of ten, on slats *i*, which slats are connected at their ends to legs *j* of a series of toothed bars *K*, which legs are stood upon the plate *G* aforesaid and are of a distance apart equal to the aggregate width of a series of perforating punches viewed in side elevation, as clearly shown in Fig. 1, the arrangement of these punches being similar to the characters in a column on the indicator-sheet. Each bar *K*, whether toothed or otherwise, its legs *j* and the slat *i* in connection with the legs are collectively a rack and so designated hereinafter. The slot in each punch is of sufficient length to permit a vertically reciprocative play of said punch when the head of same is in register with one of the bridge-pins aforesaid, and the several racks being in normal position, the innermost punch of each series is thus registered. The several punches in each series correspond to the characters of the notation aforesaid, the cipher-punch being innermost and the others in regular order of progression from one to nine outward from said cipher-punch, as indicated by numerical characters in Figs. 1 and 3.

The bar *K* of each rack is provided with a stop-lug *k* normally opposed by a counterweighted trip-bar *L* in pivotal suspension from the top of the main casing *M* of the machine, and the heads of all the cipher-punches are normally in line under an impact-end of a rocker-frame *N* loose on a rod fastened at its extremities in the side standards of the main-frame, a lug of a lever-arm *m* of the rocker-frame being in the path of a crank *O* to which further reference is had hereinafter. The casing *M* is provided with a guide-slot for the lug of said lever-arm. One leg of each rack is connected to an end of a spiral-spring *P* that has its other end connected to a hook-pin of a drum *Q* fast on a spindle having its bearings in the side standards of the main-frame. The other leg of each rack is connected by a cord or other flexible device *n* and a spiral-spring *R* to eyes with which the end-piece *E* of the main-frame is provided. The flexible device is trained on a sheave *o* mounted in an end recess of the base of said frame and the spring

R resists pull of the spring *P* aforesaid. Fast on the spindle of the drum *Q* is a spur-pinion *S* in mesh with a spur-gear sector *T* rigid on a spindle *O'* extending from the crank *O* and having its bearings in the side standards of the main frame. 70

Over the trip-bars *L* aforesaid, the top of the casing *M* is provided with parallel rows of apertures, nine in each row over the same trip-bar as shown in Fig. 1, at regularly recurring intervals apart, and these apertures are in register with corresponding apertures in an angular plate *U* fastened on said casing to therewith form a chamber having a preferably flaring opening as shown in Fig. 1, the spacing of said apertures being similar to the columns and numerals 1 to 9 in each on the indicator-sheet. The plate *U* is provided with guide-posts *p* engaging spiral-springs *q* that oppose eye-lugs *r* of an auxiliary-casing *M'* these lugs being provided with vertical slots engaged by stop-lugs *s* of said posts, whereby play of the auxiliary casing is limited in opposite directions. Guided in the apertures of the plate *U*, and in the bottom and a partition of the auxiliary-casing *M'* are spring-controlled pins *t* movable downward with said auxiliary-casing to depress trip-bars *L* and come in the paths of rack-bar lugs *k*, except as prevented by an indicator-sheet laid in the space between the main-casing and plate *U* aforesaid. The auxiliary casing is pressed down by the operator of the machine against the resistance of the springs *q* and returned to normal position by said springs on removal of the pressure. 95

The amount of a sale is primarily recorded by punching out characters in columns of an indicator-sheet. For instance, if the sale amounts to one dollar and twenty-five cents, the characters 1, 2 and 5 respectively of the hundreds, tens and units columns of the indicator-sheet are punched out, as shown in Fig. 9, and the detail of the sale may be indicated by writing on a sales-ticket *B* after which said sheet and ticket are properly inserted in the machine, the sheet in the space under the plate *U* and the ticket in the space under the plate *G* of said machine. The indicator-sheet is put in the machine display side uppermost and nine end first, all the character and punch-holes in said sheet, excepting those of the cipher-row, being then in register with the pins *t* 110 in the auxiliary frame aforesaid. The sales-ticket is also put in said machine, display-side uppermost, to have the broad transverse margin thereof in register with the cipher-punches and guide-apertures for the pins of same. The auxiliary casing is now pressed down, and the spring-controlled pins therewith in register with the punch-holes in the indicator-sheet will descend through said holes to depress corresponding trip-bars *L*. 130

and thus release the relative racks, the remaining pins being held back by said indicator-sheet. The crank O is now actuated in the proper direction and the result is a pull of the released racks as far as the pins holding down trip-arms will permit thus bringing punches corresponding to the holes in the indicator-sheet under the impact-end of the rocker-frame N, and thereafter said crank, acting on the lever-arm m of said rocker-frame, causes a depression of all the punches in register with the heads of the bridge-pins f, whereby corresponding numerical characters are punched in the sales-ticket to permanently record the amount of sale predesignated by punching of said indicator-sheet, such a result being shown in Fig. 10, where the sales-ticket appears perforated to record a sale amounting to one dollar and twenty-five cents in the order of units, tens, hundreds. It is intended that the indicator-sheet shall be retained as a permanent record of the amount of the sale, and that the sales-ticket shall be delivered to the customer with the goods purchased, it being preferable to correspondingly number said sheet and ticket to facilitate future comparison of same.

In mesh with the toothed bar K of each rack is a spur-wheel V, and all these spur-wheels V are loose on an arbor W that has its bearings in the side-standards of the main-frame of the machine, one end of said arbor being squared for the engagement of a turning-key or crank. The spur-wheels V are shown provided with elongated hubs by which they are suitably spaced on their supporting-arbor, and said wheels are in the order of units, tens, etc. Fast on the same arbor is a spur-wheel X of a gear-train comprising similar wheels severally fast upon other suitably arranged rotary arbors parallel to each other and the one W aforesaid, said arbors being in the order of units, tens, etc.

The units spur-wheel has slip-clutch connection with a hollow units register-wheel Y, loose on the same arbor and provided with a tappet u alined with the cipher-character of said register-wheel, this tappet being engageable, once in each revolution, with one of ten suitably spaced notches of another register-wheel Z loose on the tens-arbor, and likewise this tens-arbor units-register-wheel multiplies onto another units register-wheel loose on the hundreds-arbor, the notches of each multiplying-wheel being alined with the numerical characters of same. This units-register-mechanism may be continued indefinitely, in practice.

The tens, hundreds and other loose spur-wheels on the units-arbor W are respectively in gear-train with spur-wheels loose on the arbors in the ascending order of tens, hundreds, etc. above specified, and each of the latter spur-wheels is in slip-clutch-connec-

tion with a register-wheel similar to the one Y and which multiplies onto another such wheel upon the next arbor, that may in turn (as shown in all but one instance) multiply onto another suitably arranged register-wheel and so on indefinitely.

To prevent overrunning or back-lash of the register-wheels, detents v are employed in connection with the top of the machine-casing M to engage the notches of said wheels, as shown in Fig. 1, and the casing top is suitably apertured to provide for viewing said register-wheels, the cipher-character of each wheel being normally at the view aperture.

The detail of the slip-clutch connection of spur and register-wheels is shown in Fig. 6, a spring-controlled dog w in pivotal connection with the spur-wheel hub being in engagement with one of a series of ten ratchet-teeth equi-distant apart on the inside of the register-wheel. Each of the register-mechanism arbors is provided with a cam-groove x longitudinally thereof, and each register-wheel is provided with a side-housing y for a spiral-spring z controlling a stop-pin z' engageable with the cam-groove of the corresponding arbor, this detail being clearly shown in Fig. 8. The spring-controlled stop-pin of each register-wheel does not interfere with the step-by-step rotary movement of said wheel, but if the corresponding arbor be turned, in the proper direction, its engagement with said pin will serve to bring the cipher-character of the said wheel to normal position, in one revolution of said arbor regardless of the position of said character at the commencement of the revolution. Because of the gear-train connection of the units-arbor with all the other arbors of the register-mechanism, the proper turning of said units-arbor will result in a simultaneous setting of all the register-wheels to show their cipher-characters in normal position.

From the foregoing it will be understood that a registration of the money value of each sale is accomplished, as a result of movement on the part of racks above specified, these racks being returned to normal position by recoil of springs in connection therewith, after release of pressure on the auxiliary-casing aforesaid, and the arrangement of the register-wheels is such that those indicating tens of cents are all on one arbor, those indicating hundreds of cents on another arbor, and so on up to the highest multiple of cents for which the register-mechanism is designed, in order to facilitate casting up of the total registration of the machine at any time. In taking off the total amount registered, the amount indicated by the units register-wheel for cents is first noted, the unit of the sum indicated by the

register-wheels for tens of cents next noted to the left of the previous notation and the tens of this sum, if such there be, carried over into the addition of the sum indicated by the 5 register-wheels for hundreds of cents, the unit of the latter sum noted to the left of that for tens of cents and so on until the sum indicated by the register-wheels for the highest 10 numerical order of cents is noted in full to the left of the previous notations, the reading of all the notations being the grand total 15 in cents, and decimal dollars and cents of the registration by the machine in which recording and registering operations are predetermined by suitably punched indicator-sheets.

Various changes of detail in the machine 20 may be made without departure from my invention as pointed out in the claims of this specification, it being understood that said machine may be restricted to a recorder or register instead of a combination of both as herein shown.

I claim:

25 1. A machine provided with spaces for the reception of a perforated indicator-sheet, and a sales-ticket, independent recording devices adjustable in series, means governing predetermined release and stop of any one or all of said series of recording devices and controlled as to operation by means of said indicator-sheet lodged in the space therefor aforesaid, and means permitting and controlling a reciprocation of aligned recording 30 devices of the several series in opposition to said sales-ticket arranged in the space provided for the same.

40 2. A machine provided with spaces for the reception of a perforated indicator-sheet and a sales-ticket, independent recording devices adjustable in series, means governing predetermined release and stop of any one or all of said series of recording devices and controlled as to operation by means of said indicator-sheet lodged in the space therefor aforesaid, means permitting and controlling a reciprocation of aligned recording devices of the several series in opposition to said sales-ticket arranged in the space provided 45 for the same, and a registering mechanism operative incidental to adjustments of the various series of recording devices aforesaid.

50 3. A machine comprising a series of movable racks, recording devices in series on suitable guides and each series movable with a corresponding rack, spring-controlled yielding bridges constituting parts of the guides in position to oppose aligned recording devices of the several series, a rotary drum, a pull-spring connecting each rack with the drum, a back-draw spring also connected to each rack, means by which the several racks are locked in normal position, means governing predetermined release and 55 stop of any one or all of said racks, and

means for impacting recording devices in register with said bridges.

4. A machine comprising a series of movable racks, suitably controlled pivotal trip-bars arranged to normally resist propulsion 70 of the racks, recording devices in series on suitable guides and each series movable with a corresponding rack, spring-controlled yielding bridges constituting parts of the guides in position to oppose aligned recording 75 devices of the several series, means for propelling and retracting the racks and recording devices therewith, means for impacting recording devices in register with said bridges, and a reciprocating device carrying 80 spring-controlled pins in series registered with guide-apertures over the trip-bars; in combination with a punched indicator-sheet temporarily supported in the machine to obstruct descent of all the pins aforesaid not in register with a punch-hole or holes of said sheet, the unobstructed pin or pins serving to move a corresponding trip-bar or bars out of normal position and limit propulsion of a corresponding rack or racks.

5. A machine comprising a series of movable racks, suitably controlled pivotal trip-bars arranged to normally resist propulsion of the racks, recording devices in series on suitable guides and each series movable with a corresponding rack, spring-controlled yielding bridges constituting parts of the guides in position to oppose aligned recording 95 devices of the several series, means for propelling and retracting the racks and recording devices therewith, means for impacting the recording devices in register with said bridges, multiple register mechanisms in gear with the racks, and a reciprocating device carrying spring-controlled reciprocal pins in series registered with 100 guide apertures over the trip-bars; in combination with a punched indicator-sheet temporarily supported in the machine to obstruct descent of all the pins aforesaid not in register with a punch-hole or holes of said sheet, the unobstructed pins serving to move a corresponding trip-bar or bars out of normal position and limit propulsion of a corresponding rack or racks.

6. A machine comprising a series of racks and mechanism controlled by same, a rotary drum, spiral-springs connecting the racks and drum, means normally holding the racks against draw of said springs, means for predetermined release of any rack or racks and for variously limiting the propulsion of same, and other springs in connection with said racks contrary to those aforesaid.

7. A machine comprising independent recording devices adjustable in series, means whereby the several series of recording devices are locked in normal position, means governing predetermined release of any one or all of said series, independent spring- 125

controlled yielding supports for aligned recording devices of the several series, and an impactor for said devices in register with said supports.

5 8. A machine having a series of independent multiple register mechanisms comprising wheels so arranged that those indicating tens in the several mechanisms are on the same arbor, those indicating hundreds 10 on another arbor and so on up to the highest multiple of the unit, means whereby all of said wheels may be simultaneously returned to normal position; and a punched indicator-sheet engageable with the machine 15 to determine an operation of any one or more of said mechanisms.

9. A machine of the character described provided with a space for the reception of a perforated entry sheet and a space for 20 the reception of a sales ticket, a recording mechanism comprising a plurality of recording devices controlled as to selection and alinement by means of said entry sheet lodged in the space therefor aforesaid, and 25 means for actuating said recording devices

to effect the operation of the same upon said sales ticket arranged in the space provided for the same.

10. A machine of the character described provided with a space for the reception of 30 a perforated entry sheet and with a space, for the reception of a sales ticket, a recording mechanism comprising a plurality of recording devices controlled as to selection and alinement by means of said entry sheet 35 lodged in the space therefor aforesaid, means for actuating said recording devices to effect an operation of the same upon said sales ticket arranged in the space provided for the same, and a registering mechanism co- 40 operative with said recording mechanism.

In testimony that I claim the foregoing I have hereunto set my hand at Milwaukee in the county of Milwaukee and State of Wisconsin in the presence of two witnesses. 45

EDWARD J. BRANDT.
